UNITED STATES PATENT OFFICE.

WILLIAM J. BRENNAN, OF LYNN, MASSACHUSETTS, ASSIGNOR, BY MESNE ASSIGNMENTS, TO
THOMAS G. PLANT, OF BOSTON, MASSACHUSETTS.

WORK-REST.

No. 908,143.

Specification of Letters Patent.

Patented Jan. 12, 1909.

Application filed August 1, 1907. Serial No. 386,565.

To all whom it may concern:

Be it known that I, WILLIAM J. BRENNAN, a citizen of the United States, residing at Lynn, in the county of Essex, State of Massachusetts, have invented an Improvement in Work-Rests, of which the following description, in connection with the accompanying drawings, is a specification, like letters on the drawings representing like parts.

19 The invention to be hereinafter described relates to work rests used in the art of boot and shoe making and more particularly to the means for securing to such rests the covering material employed to protect the work.

15 The object of the present invention is to provide a work rest with simple and efficient means for securely connecting the covering material thereto, and, as a further object, to enable such material to be evenly stretched 20 about the support without danger of injury, all as will more fully appear in the following description of one embodiment of the invention.

In the drawings:—Figure 1 is an elevation 25 of a work rest in the form of a toe pad selected as an illustration of the present invention. Fig. 2 is a transverse section thereof on the line $\alpha-\alpha$ Fig. 1.

The post A; the supporting stem B, and 30 the adjusting nut C may be of any usual or desired construction, and being well known to those skilled in the art need no further description.

35 Mounted in suitable manner upon the stem B is the support or saddle 1, upon which is placed the usual covering of flexible material to give protection to the shoe being treated; such material in the present illustration being formed of a layer of felt 40, 2, and a superposed layer of soft leather 3, it being understood, however, that the invention is not restricted in this respect. The support or saddle 1 may be of any appropriate or desired form but is preferably curved 45 as shown and provided with the downturned edge portions 4, 4, about which the edges of the flexible covering are passed, as best shown in Fig. 2.

Beneath the support 1, regardless of its 50 particular shape is a holding plate 5 adapted to engage the edge portions of the flexible covering as indicated in Fig. 2. In the character of support or saddle illustrated, one of such holding plates is preferably disposed on each side of the central or support-

ing stem B, but obviously the number or general character of such plates to adapt them to the particular support or saddle may vary. The edges of plate 5 are preferably provided with teeth or serrations 6, 60 which when the plate 5 is forced upward will embed themselves in the flexible cover, as indicated in Fig. 2.

Extending from the underside of the support or saddle 1, is a boss 7 into which is 65 screw-threaded the adjusting screw 8, said screw being first passed through the holding plate 5, as will be readily understood. In case a plurality of these holding plates are employed, obviously there will be a corresponding number of bosses 7 and screws 8, as indicated in Fig. 1.

From the construction illustrated and described as one embodiment of the present invention it will be noted that the edge portions of the protecting and flexible cover are carried down and about the lower edge portions 4 of the curved support 1, and that the upward converging lower surface of the support 1, causes the holding plate 5 to engage 80 the edge portions of the flexible cover as said plate is adjusted by the screw 8. As the plate 5 is carried upward under the adjusting action of screw 8, the converging lower surface of the support will cause said plates to 85 bite more firmly into the covering material, so that as the stretch or strain upon the cover becomes greater there is a corresponding increase in the holding action of the holding plate 5. It will also be noted that the described construction provides means not only 90 for readily adjusting and holding the flexible cover upon the support, but also means for enabling ready removal of an old or worn-out cover and the application of a new one, and for 95 adjusting the tension of said cover at any time by merely turning the adjusting screw. 100

What I claim, is:—

1. A work rest comprising a transversely curved support; a protecting cover of flexible material passed about said support, a holding plate disposed below the concaved portion of said curved support and engaging the flexible cover near the turned edge portions thereof, and means movable within the 110

concaved portion of said support for exerting a pulling force upon such edge portions to cause the cover to be drawn taut about said support.

5 2. A work rest comprising a curved support having a boss on its concaved portion, a cover of flexible material for said support, a holding plate engaging the flexible material adjacent the edge portion thereof on the 10 opposite side of said support, and means engaging said boss for forcing said holding plate towards the support as and for the purpose described.

3. A work rest having under converging 15 side surfaces, a flexible cover for said support having edge portions turned about the edge portions of the support, a holding plate of a length less than the distance between the edge portions of said support and engaging 20 the flexible cover below the support, and a screw for forcing the said holding plate towards and the material of the cover against the under converging surfaces of said support.

25 4. A work support having an upwardly converging lower surface, a flexible cover for said support, a holding plate of less length than the distance between the downturned edges of said support, and means for 30 adjusting the holding plate to cause the edge

portions thereof to bite or clamp the flexible cover between the edges of said holding plate and the lower curved surface of the support.

5. A work support comprising a saddle 35 having downturned edge portions and provided with a boss, a flexible cover for said saddle having its edges turned about the downturned edge portions of said saddle, a plate engaging the flexible cover between the 40 downturned edge portions of said saddle, and means engaging the boss and said plate to draw the cover about the saddle.

6. A work support comprising a saddle having downturned edge portions and provided with a boss between said edge portions, a flexible cover for said saddle having its edges turned about the edge portions of the saddle, a plate engaging the flexible cover between the downturned edge portions 50 of said saddle, and a screw passed through said plate and engaging the said boss to draw the cover about the saddle.

In testimony whereof, I have signed my name to this specification, in the presence of 55 two subscribing witnesses.

WILLIAM J. BRENNAN.
